UNITED STATES PATENT OFFICE.

FRED H. DOERR, OF GRAND RAPIDS, MICHIGAN, ASSIGNOR TO CHENEY TALKING MACHINE COMPANY, OF CHICAGO, ILLINOIS, A CORPORATION OF ILLINOIS.

AUTOMATIC MOTOR STOP.

Application filed April 29, 1922. Serial No. 557,415.

To all whom it may concern:

Be it known that I, FRED H. DOERR, a citizen of the United States, residing at Grand Rapids, in the county of Kent and State of Michigan, have invented certain new and useful Improvements in Automatic Motor Stops, of which the following is a specification.

This invention relates to a new and improved automatic motor stop and more particularly to a mechanism adapted to automatically stop the motors of a talking machine upon cessation of movement of the tone arm at the end of a record.

As is well known in the art, the records of talking machines comprise a spiral groove which groove ceases at the end of the playing portion of the record. It is desirable to provide automatic means for stopping the motor and consequently the rotation of the record when the stylus reaches the end of the record groove.

Certain mechanisms have heretofore been used, such, for example, as that disclosed in my Patent No. 1,489,487, which cause a brake to act upon the turn-table at the completion of the record. This method of stopping a machine is open to the objection that no means are provided for stopping the motor when the turn-table is removed from the machine for the purpose of oiling or inspecting the mechanism.

In order to simplify the operation of the apparatus, it is desirable to provide means whereby the stop mechanism may be disengaged by movement of the tone-arm. It is also desirable to provide means whereby the stop mechanism will not become operative when the sound box is held over the outer edge of the record in placing it upon the record when starting to play.

Since for some purposes it may be temporarily undesirable to have the stop mechanism in operation, as, for example, when using a device for repeating records, I have provided means whereby my stop mechanism may be rendered inoperative. Since it may at times be desirable to immediately stop rotation of the turn-table, other than at the end of a record, I provide a manually operable friction brake acting on the turn-table. In the preferred form, the operating lever for this brake also serves to release the motor stop mechanism.

It is an object of the present invention to provide an automatic stop adapted to operate upon the motor and to positively stop the operation of the motor upon cessation of movement of the traversing member or tone arm.

It is a further object to provide a stop of this character in which cushioning means are interposed between the stop and the motor so that the motor may not be injured by too sudden a cessation of movement.

It is a further object to provide means of this character in which the stop may be released by movement of the traversing member or tone arm.

It is also an object to provide means whereby the mechanism is rendered inoperative during a predetermined range of movement of the tone arm.

It is a further object to provide in connection with such mechanism, manually operable means whereby the mechanism may be rendered inoperative.

Another object is to provide a manually operable means adapted to disengage the stop mechanism.

An additional object is to provide an auxiliary friction brake acting upon the turn-table and preferably operated by a member which also serves to release the stop mechanism.

Other and further objects will appear as the description proceeds.

I have illustrated a preferred embodiment of my invention in the accompanying drawings, in which—

Figure 1 is a plan view showing a talking machine with my mechanism applied thereto, the turn-table being cut away to show the mechanism, the mechanism being shown in the stop position;

Figure 2 is a view similar to Figure 1 but showing a modified form of the device, the mechanism being in an operating position;

Figure 3 is an enlarged view on line 3—3 of Figure 2;

Figure 4 is a section taken on line 4—4 of Figure 2; and

Figure 5 is an enlarged view showing the mechanism of Figure 2 in the starting position.

Referring now to the form of the device shown in Figure 1, the tone arm 7 carries the sound box 8 and is supported by collar

9 resting on flange 10. The flange 10 is secured to the cabinet top 11. The arm 12 is rigidly connected to the collar 9 and is thus rotated with the tone arm. Rack bar 13 has one end pivoted at 14 to the arm 12 and its opposite end pivoted at 15 to the link 16. The link 16 is pivoted to the lever 17 which is pivoted upon the vertical stud 18, the stud being secured to the motor-board 62. The lever 17 has a second arm 19 having a rounded outer end 20, the purpose of which will be discussed hereafter.

The rack bar 13 is provided with a rack 21 which engages the recessed teeth of the quadrant 22, being held in engagement therewith by guide stud 77. The quadrant is pivoted upon shaft 23 upon which is also pivoted the friction arm 24. This arm 24 is maintained in frictional engagement with the hub of the quadrant 22 by means of the spring clip 25.

The free end 26 of the friction arm 24 fits into an opening 27 in a downwardly deflected portion of the stop member 28 as best shown in Figure 3. The stop member 28 is pivoted upon the screw 29 fitting in stud 30. This stop member is provided with the stop arm 31, having a down-turned outer end, and in the form of device shown in Figure 1, it is also provided with the starting arm 32, the latter having an upturned end. The member 28 is also provided with the spring receiving extension 33 which fits into a notch 34 in the limiting member 35. The spring 36 connects the portion 33 of the stop member and the spring receiving extension 37 of the control member 38, which member is also pivoted upon the screw 29. The control member is provided with a struck up lug 39 which fits in a notch 40 in the stop member and with an operating arm 60, as best shown in Figure 5.

The turn-table spindle 41 is provided with a small gear 42 meshing with the larger gear 43 which latter rotates about the stud 18. As best shown in Figure 4, the larger gear wheel 43 is rigidly connected to the hub 44 and the star wheel 45 is rigidly connected to the upper portion of this hub. The cam carrying member 46 rotates freely about the hub 44 between the gear 43 and star wheel 45. As best shown in Figure 5, this member 46 is provided with the studs 47 and 48 upon which are pivoted the links 49 and 50 carrying rollers 51 and 52 which latter engage the periphery of the star wheel 45. These rollers are maintained in engagement with the star wheel by the springs 53 and 54, the opposite ends of which are secured to the upturned portions 55 and 56, respectively, of the member 46. The member 46 also carries the stop lug 57 and the cam 58.

In the form of device shown in Figures 2 and 5, the link 16 is provided with the lug 59 which is adapted to engage the stop

arm 31 when the tone arm is swung outwardly to the extreme limit of its movement. The control member 38 is provided with the control arm 60, the end of which is adapted to engage the portion 20 of lever 19 when the tone arm is swung adjacent the outer edge of the turn-table.

Referring now to Figure 1, the slide lever 61 is held in frictional engagement with the motor-board 62 by the heads of the studs 63, the studs fitting in elongated slots. The outer end of this slide lever is provided with the handle 64 for manual operation. The inner end of the lever 61 is provided with the upwardly extending portion 65 adapted to engage the inner edge of the control arm 60.

Referring again to Figure 1, the slide 66 is secured to the motor-board 62 by the studs 67 which coact with the slots 68 to permit a limited movement of the slide. The slide is provided with the starting arm 69 adapted to engage the arm 32 of the stop member 28. The brake member 70 is pivoted upon the slide 66 and is provided with the brake pad 71 and operating handle 72. The member 70 is also provided with the lug 73 adapted to engage the lug 74 of the slide 66 when the brake is in the off position. The spring 75, one end of which is connected to the member 70 and the opposite end of the stud 76, secured to the motor-board, serves both to maintain the brake in either the on or off position and also to retain the slide 66 at one end of its normal movement.

In the operation of both forms of the device, the gear wheel 43 is rotated by the gear 42 upon the turn-table spindle 41. This wheel 43 carries with it in its rotation the star wheel 45. The member 46 is also carried with the wheel 43 in its rotation, due to the engagement of the cam rollers 51 and 52 with the star wheel. The stop lug 57 and the cam 58 are thus rotated.

As the tone arm is moved inwardly by the spiral groove upon the record, the rack bar 13 is drawn outwardly. It thus serves to rotate the quadrant 22 in the counterclockwise direction about its pivot 23. The friction arm 24 is frictionally clamped to the quadrant and hence tends to swing with the quadrant in the counterclockwise direction. The end 26 of the friction arm engages the stop member 28 and tends to rotate that member in the clockwise direction. The movement of the member 28 in the clockwise direction is limited by the engagement of the spring retaining lug 33 with the side of the notch 34 in member 35. This notch permits the member 28 to swing to the position shown in Figure 5. In this position, the end of the stop arm 31 is clear of the path of the stop lug 57. The down-turned end of the stop arm 31 is, however, engaged by the cam 58, and the arm is

swung in the counterclockwise direction by the cam.

So long as the tone arm is moving inwardly and consequently the friction arm 24 is moving in the counterclockwise direction, the engagement of the arm 24 with the stop member 28 will move the stop arm 31 out of the path of stop lug 57. When, however, the inward movement of the tone arm ceases, 10 due to the stylus having reached the inner end of the record spiral, or when the tone arm is swung out from the record and remains still, no movement will be transmitted through friction arm 24 to the stop arm, and 15 the stop arm will remain in the position in which it is placed by the cam 58 until the gear 43 has completed a rotation and brought the lug 57 against the end of the arm. The rotation of the member 46 will 20 thus be positively stopped. Further rotation of the gear 43 will be resisted by the spring held engagement of the rollers 51 and 52 with the cam surfaces of the star wheel 45.

25 It will be observed that these two rollers are staggered so that they engage different relative portions of the cam surfaces and will not simultaneously drop off the end of cams. This spring resistance will yieldingly stop 30 the rotation of the gear wheel 43 and consequently stop the motor driving the spindle 41.

When the tone arm is swung over the outer or beginning portion of the record, the 35 cam 20 will be brought to the position in which it is shown in Figure 2. It here engages the arm 60 of the control member 38 and swings that arm in the clockwise direction. This movement of the control member 40 puts a tension upon the spring 36, and consequently the spring yieldingly urges the stop member 28 to the limit of its movement with the lug 33 against the left side of the notch 34. This spring tension upon 45 the stop member is sufficient to overcome the frictional action transmitted by the arm 24 so that as soon as the stop arm 31 clears the cam 58, the arm will be drawn by the spring back to the position in which it is 50 shown in Figure 5. Consequently, while the cam 20 engages arm 60, the stop mechanism will not operate regardless of whether or not the tone arm is moving inwardly. The engagement of lug 39 upon member 38 with 55 the notch 40 in member 28 limits the relative movement between these two members, and together with spring 36 insures their normally moving as a unit.

Referring now to Figure 1, when the slide 60 61 is pulled outwardly by means of its handle 64, the inner upturned end 65 will pull outwardly upon the arm 60. This will have the same result as when that arm is thrust outwardly by the cam 20. Consequently, 65 pulling the slide to its outer posi-

tion serves to put the automatic stop out of operation.

When the automatic stop is in the stopped position, the arm 31 will be engaging the stop lug 57 as shown in Figure 1. In order 70 to start the form of device shown in Figure 1, the lever 72 is swung in the clockwise direction until the lug 73 engages the lug 74. This movement releases the friction brake 71 from the turn-table. The 75 lever 72 is further moved upwardly to the left as seen in the drawing, thus moving with it the slide 66 and the starting arm 69, through the movement permitted by slots 80 68. The arm 69 engages the upturned end of the arm 32 and rotates the stop member 28 in the clockwise direction a sufficient amount to disengage the arm 31 from the lug 57. If the turn-table has been stopped solely by the automatic stop, the lug 73 will 85 be in engagement with the lug 74 and only the second movement of the lever 72 described will be necessary to start the machine.

The form of the device shown in Figures 2 and 5 is identical with that of Figure 1 with the exception of the starting mechanism. In the form of the device shown in Figures 2 and 5, the machine is started by 90 swinging the tone arm outwardly until the lug 59 engages the arm 31 and thrusts the latter out of engagement with the lug 57.

The forms of the device shown are to be understood as illustrative only, and I reserve the right to make such changes and 95 modifications as come within the scope of the appended claims.

I claim:

1. In combination with a motor and a traversing member, stop mechanism for said 100 motor adapted to impose a positive cushioned resistance upon the motor, and means adapted to operate the stop mechanism upon cessation of movement by the traversing member.

2. In combination with a motor and a traversing member, stop mechanism for said motor adapted to impose a spring resistance upon the motor, and means adapted to operate the stop mechanism upon cessation of movement by the traversing member.

3. In combination with a motor and a traversing member, a stop arm operated by 110 said traversing member, a stop lug moved by said motor and having a spring connection therewith, and means whereby the stop arm engages the stop lug to stop the motor upon cessation of movement by the traversing member.

4. In combination with a motor and a traversing member, a stop arm yieldingly urged in one direction by movement of the traversing member, a member rotated by the motor, a second member carrying 115 a stop lug, a yielding connection between 120 125 130

- said members whereby the second member is rotated by the first, a stop lug carried by the second member, and cam means operated by the motor and adapted to periodically move the arm in the opposite direction and into engaging position relative to the lug.
5. In combination with a motor and a traversing member, a stop arm yieldingly urged in one direction by movement of the traversing member, a member rotated by the motor, a second member carrying a stop lug, a yielding connection between said members whereby the second member is 10 rotated by the first, a stop lug carried by the second member, and cam means carried by the second member and adapted to periodically move the arm in the opposite direction and into engaging position relative to the lug.
15. In combination with a motor and a traversing member, two members mounted on a common axis, a rigid drive connection between the first member and the motor, a yielding drive connection between the two members, and means adapted to positively stop movement of the second member upon cessation of movement by the traversing member.
20. 7. In combination with a motor and a traversing member, two members mounted on a common axis, a rigid drive connection between the first member and the motor, a star wheel carried by the first member, 25 and spring pressed cam rollers carried by the second member in engagement with the star wheel, forming a yielding drive connection between the two members, and means adapted to positively stop movement of 30 the second member upon cessation of movement by the traversing member.
35. 8. In combination with a motor and a traversing member, a stop arm operated by said traversing member, a stop lug moved 40 by said motor, means whereby the stop arm engages the stop lug to stop the motor upon cessation of movement by the traversing member, and manually operable means adapted to disengage the stop arm from 45 the stop lug.
45. 9. In combination with a motor and a traversing member, a stop arm operated by said traversing member, a stop lug moved by said motor, means whereby the stop 50 arm engages the stop lug to stop the motor upon cessation of movement by the traversing member, and means whereby said 55 arm engages the stop lug to stop the motor upon cessation of movement by the traversing member, and means whereby said means is rendered inoperative through a

certain range of movement of the traversing member.

10. In combination with a motor and a traversing member, a stop arm operatively associated with the traversing member, a stop lug operated by the motor, mechanism whereby the stop arm engages the stop lug to stop the motor upon cessation of movement by the traversing member, and manually operable means adapted to prevent engagement between the stop arm and stop lug.

11. In a sound reproducing machine, a tone arm, a motor, a turn-table rotated by the motor, a stop arm operatively associated with the tone arm, a stop lug operated by the motor, mechanism whereby the stop arm engages the stop lug to stop the motor upon cessation of movement of the tone arm, and manually operable means adapted to prevent effective operation of said mechanism.

12. In a sound reproducing machine, a tone arm, a motor, a turn-table rotated by the motor, a stop arm operatively associated with the tone arm, a stop lug operated by the motor, mechanism whereby the stop arm engages the stop lug to stop the motor upon cessation of movement of the tone arm, manually operable means adapted to prevent effective operation of said mechanism, and a manually operable friction 90 brake for the turn-table.

13. In a sound reproducing machine, a tone arm, a motor, a turn-table rotated by the motor, a stop arm operatively associated with the tone arm, a stop lug operated by the motor, mechanism whereby the stop arm engages the stop lug to stop the motor upon cessation of movement of the tone arm, and manually operable means adapted to disengage the stop arm from 100 the stop lug.

14. In a sound reproducing machine, a tone arm, a motor, a turn-table rotated by the motor, a stop arm operatively associated with the tone arm, a stop lug operated by the motor, mechanism whereby the stop arm engages the stop lug to stop the motor upon cessation of movement of the tone arm, a manually operable friction brake for the turn-table and a manually operable lever 110 adapted to release said brake and to disengage the stop arm from the stop lug.

Signed at Grand Rapids, Michigan, this 25th day of April, 1922.

FRED H. DOERR.
